UNITED STATES PATENT OFFICE

JOSEPH BLONDIN, OF LOS ANGELES, CALIFORNIA

THERMOAEROSTAT

Application filed December 16, 1929. Serial No. 414,495.

My immediate invention relates to aircraft of the lighter-than-air type, (commonly called a "montgolfier" or hot-air balloon) designed to carry its own fuel and air-heating 5 furnace; whereby it can accomplish long voyages until the fuel is exhausted.

So far as I am aware, all previous "voyaging montgolfiers" (dating from 1783), were "straw-burners," and this bulky and dangerous 10 "flaming" fuel led to their being banned from use as "cross-country" air-transport mediums, in favor of hydrogen and coal-gas balloons; the only type that has persisted being the familiar county fair balloon, whose 15 air is heated in a "ground" furnace and which carries no fuel charge, into the atmosphere.

Another form of montgolfier, dating from 1853, when liquid hydrocarbon fuels became 20 generally available, comprised attempts to use this ideal concentrated fuel, with its high heat-content. But, perhaps because of the last named characteristic, all these attempts took the form of developing a rival of the gas- 25 balloon, through the use of "Bunsen"-type burners, designed to superheat the air, with the aim of securing a lift per unit volume, equivalent to hydrogen, or at least, to coal-gas.

None of the aforementioned types of montgolfiers embodied ideas or attempts to improve the balloon-proper, that is to say, the "bag" which contains the air to be heated, this being merely assembled and coated with 35 some starch or pigment "filler" designed solely to increase the bag's impermeability to the heated air within it; nor ideas or attempts to "condition" the bag's contained air to make it more conductive and absorbent of heat; nor 40 ideas or attempts to eliminate the original defect of the montgolfier of 1783, "naked-flame" burners or furnaces; nor ideas or attempts to promote efficient circulation of the air within the bag, or promote quick and 45 wide dissemination of heat throughout the air within the bag; nor ideas or attempts to govern or control the circulation of air within the bag, nor to govern or control the compression and release of compression of the 50 air within the bag; and all of these preceding

machines were devoid of ideas and attempts to make the machine as a whole more practical to handle, inflate, launch, control, and "land." Up to the present writing, the original and traditional method of launching 55 these machines is used, which involves the use of high poles, rope and tackle, and numerous volunteer assistance.

Obviously, montgolfiers produced and operated in the above mentioned manner have 60 numerous disadvantages not fitting them for independent operation from any open field encountered in cross-country voyages, with heater means carried aboard and within the capacity of the machine's pilot and helper, or 65 helpers: a condition absolutely essential to montgolfier operation, if the latter is to be developed as a practical air-transport machine.

It accordingly is an object of my present invention, to eliminate effectively all the above named disadvantages, and provide principles and processes and means to create a really new type of aircraft (which I call a "thermo-aerostat" or heat-balloon) which shall be superior in every respect to every type of montgolfier so far developed, and while making no attempt to rival hydrogen or coal-gas balloons in lifting capacity per unit of volume, will be materially cheaper to construct and 70 operate, and will provide a type of aircraft ideal for the study and development of meteorology, aerial photography, mapping, exploration, cross-country voyaging, and every other purpose within the scope of "lighter- 75 than-air" aircraft.

To this end the balloon-proper of my thermo-aerostat is processed, with the object of making it a superior container of hot air, and a retainer of the heat of said air. A distinctive feature of this invention, therefore, is the purpose and process whereby the balloon proper or "bag", is coated inside with a white lacquer that not only impermeabilizes it, but makes it reflect and radiate the heat of its contained air back into the air-mass and materially reduce the loss of heat by radiation from its exterior; and is coated outside with a black, orange, or other appropriate colored lacquer designed not only to 80 85 90 95 100

weather-proof it but to make it absorb the heat of the sun and of the surrounding atmosphere. Both of these chemical and actinic processes contribute to the long life of the bag, in protecting its fabric, and both contribute to the duration of any given voyage and to economy by efficiently using and retaining the heat generated, by the furnace, and by supplementing said heat by that derived from natural outside sources; and in both cases, again, by reducing loss of heat by radiation from the balloon's surfaces.

Another object of my invention is to provide a principle and process and method of treating air that will render it more absorbent of heat than its natural state permits. Hot, dry air alone is almost perfectly transparent to heat; an insulator rather than a conductor of heat, and is therefore handicapped against efficient use in large balloons. This particular characteristic of air has operated detrimentally against my predecessors' attempts to improve the montgolfier.

On the other hand hot, dry air has a great affinity for moisture, and air plus aqueous vapor, forms a mixture well known for its heat-absorbing, conducting and consequent expansible qualities. Some vapors, vegetable odors or perfumes, and gases also, have this characteristic heat-carrying and absorbing quality. A distinctive feature of this invention, therefore, involves the use of any of said vapors, odors or gases, and particularly, the use of water-vapor (not steam), as an indirect or auxiliary heat-carrying medium, whose greater specific-heat capacity absorbs, conducts and transfers heat from the furnace to the air within the balloon, whereby a greater volume of air is heated in less time than by any other possible direct application of heat to dry-air alone; and whereby the greater expansible quality of the said mixture, per unit of heat absorbed, provides an aerostatic lifting-medium, per unit volume, much superior to the simple hot dry-air of former montgolfiers. The water vapor is produced, by, in my present method, evaporation from an annular fabric apron surrounding furnace elements, said apron being saturated with water continually drawn from a reservoir, by capillary attraction.

Another object of my invention is to provide an inclosed-flame burner or air-heating furnace, of the catalytic type, wherein refractory material is made to absorb all flames and is rendered "glowing" or incandescent thereby and is so shaped that the air is held in contact with the heating medium for a longer period of time than in all preceding types of exposed-flame burners, wherein the air to be heated merely traverses the flame.

As before stated, all previous montgolfier liquid-fuel furnaces made use of variations of "Bunsen" burners so grouped that the air

traversing the burners left the furnace in a central, ascending, coherent or compact column or pole form. My invention provides a type of furnace consisting of one or more annular or "ring-burners" including glowing or incandescent material, whereby air traversing the same and contacting the sides of the ring is heated and leaves the furnace as a continuation of the shape of the burner. That is to say, in the shape of a tube or series of concentric tubes depending on the number of ring burners used.

This ring or hollow cylinder of heated air rises, expands, and disseminates its heat to the surrounding air from both its inside and outside surfaces or walls, so to speak, thereby heating contiguous air more quickly and effectively than any central, coherent pole of hot air can possibly do, as such a central column tends to hold together, slowly losing its heat from its exterior surface only.

Another object of my invention is to provide means within the balloon the purpose of which is to intercept and prevent the hot air arising from the furnace from cohering into a central column or pole which otherwise, as in all preceding montgolfiers, would rise directly to the top of the balloon and from thence mushroom downward. A distinctive feature of this invention, therefore, is an inverted, cone-shaped diaphragm hung in the balloon's interior which causes the hot air currents to be deflected laterally or radially towards the balloon's sides, whereby hot air currents are forced to traverse the peripheral, instead of the central, mass of superincumbent air, transferring to the same the furnace-supplied heat.

Therefore the whole air-mass within the balloon can be heated throughout most efficiently; to a relatively low terminal mass-temperature, and whereby the creation of localized "hot-spots" against the balloon's envelope or surfaces, is prevented. This diaphragm is treated or lacquered white, inside and outside, and assists the balloon's interior, similarly coated, in reflecting and radiating back into the air mass, all the latter's heat rays and vibrations.

Another object of my invention is to provide a design of neck-valve, and method of admission of air into and expulsion from the balloon such as will permit of a more positive and certain control of the balloon's vertical movements. In all previous montgolfiers neck-valves proper were not used; the neck or equivalent aperture, being left permanently open, resulting in a constant flow of cold air into the balloon. A distinctive feature of this invention is the design and employment of a neck-valve which can be closed and opened, at will, but which contains, also, permanently open apertures designed to feed just sufficient air for furnace operation, or combustion. The neck-valve proper is de-

signed to be opened fully to admit fresh air to the balloon, to cool and lower the mass temperature of the balloon's contained air and cause a descent of the balloon-system as a whole, or to be closed, when desired, to prevent any further admission of cold air and consequently cause the heated air already in the balloon to circulate anew and continually through and around the furnace, to cause the balloon system as a whole to rise, or to circulate the balloon's contained air and disseminate therein just sufficient heat to maintain the air mass at a desired temperature, and at a consequent desired altitude.

15 Another result of the design and operation of this neck-valve is the re-use and circulation of the balloon's contained air, effecting, thereby, a material economy in the use of fuel, and likewise, the increased duration of 20 a given voyage as the result of fuel economy.

Another distinctive feature of the neck valve proper, is the incorporation therewith of supplementary or auxiliary valve-ports with accompanying valve-flaps normally 25 closed under tension of springs and designed to open automatically under pressure of balloon's contained air to safely relieve pressure caused either by a too rapid increase of temperature, or by expansion of the balloon's 30 contained air, due to the ascension of the balloon system as a whole, into the rarer atmosphere of higher altitudes.

A further object of this invention is to provide a design of basket or car which shall 35 carry all accommodations for pilot and passengers, all controls governing the operation of the balloon, fuel and furnace for levitation, and such features of construction as shall easily permit the attachment of the balloon-section thereto; and finally, the incorporation of a centrifugal fan or blower, whereby, after the balloon-section is attached 40 to the car-section, air is forced into the balloon, inflating same, which inflation is regulated by sand-bags applied to the balloon's 45 netting or equivalent, as in conventional gas-balloon practice. When sufficient air is thus injected into the balloon, the furnace is started and through the continued joint action of the blower and the furnace, complete inflation is effected without the use of poles, ropes, tackle, and large retinue of helpers which has so handicapped all montgolfier operations of the past. In other words, I aim to 50 provide a self-launched balloon.

Further, this invention embodies a design 55 of balloon and suspension rigging, closely following conventional gas-balloon practice, including a head-valve, rip-valve, drip-belt, and a load-ring formed by the top edge of the basket's side-walls. The conventional neck is eliminated and replaced by the furnace-flue, which is carried centrally above 60 the basket, and the balloon-section proper is

detachably fixed directly to a neck-ring forming the extreme top of the furnace-flue.

As a further feature one side of the furnace-flue, and one side of the basket, are provided with complementary skids upon 70 which the basket and furnace-system, as a whole, is designed to rest upon the ground for the purpose of facilitating the attachment of the balloon-section to said car and furnace-system, and for the purpose of protecting 75 the car and furnace-system from direct contact with the ground when effecting landings.

The invention consists in certain advancements in this art as set forth in the ensuing disclosure and having, with the above, additional objects and advantages, and whose construction, combination and details of means, and the manner of operation will be made manifest in the ensuing description of the herewith illustrative apparatus; it being 80 understood that modifications, variation and adaptations may be resorted to within the scope, principle and spirit of the invention as it is more directly claimed hereinafter.

Figure 1 is a side elevation of my thermoeastat invention, showing a one-quarter section removed for illustrating interior elements and arrangements of same.

Figure 2 is a plan of the furnace and surrounding parts.

Figure 3 is a plan of the basket or car showing relative position of the landing skids and other parts.

Figure 4 is a side elevation of the car laid on side skids with the balloon neck partly 100 connected to cage ring.

Figure 5 is a side elevation of the upended cage and shows the balloon connected 105 up and evenly mushroomed therearound and ready for inflation.

Figure 6 is a diagrammatic and sectional view of schematic heater and moistener.

The apparatus comprises a hot air or gas bag 2 of any suitable form, size and material, preferably a fabric which is susceptible of an exterior coat of a water-proofing and heat absorbing media, or possessing either of these properties. At the top of the bag is a suitable head valve 3 above which 110 is a spaced bonnet 4.

One or more of the usual rip valves 5 are provided, and exterior filling-loops 6, loadnets or rigging 7, a drip belt 8, and equator lines 9 are incorporated and replace the common netting.

The bottom of the bag or "balloon-section" is attachable to a stout neck-ring 10 which forms the crown of an upper cage-compartment formed by a balcony 11 which forms the roof of a lower car-compartment and is also the base supporting the heating apparatus, later described. The rim of the balcony comprises a buffer ring 13 at one side of which 115 are fixed outward and upward extending skid 120

bars 14 which rigidly join to the higher neck ring 10.

The car has an upper or load ring 16 and a bottom ring 17 these, at the side under the skids 14, having similar skids 18, so that when landing, and at other periods, the combined cage structure rides or rests on its skid side. These upper and lower cage compartments are connected by a skeleton of stiff standards 19 in columnar arrangement and extending well above and also well within the neck-ring 10 and are bent radially inward to form a flat dome 20 extending into the connected bag 2, and, as clearly shown in Fig. 5, to support 15 the superposed and collapsed fabric bag well above the ring 10, for reasons later discovered.

The rings 10—13 are also vertically connected by a fabric wall 22, which is perforated at its lower part to form numerous valve-ports 23. Entirely surrounding the wall at its base is a sleeve, lift-valve 24 which carries valve ports to register with the wall ports 23. The sleeve ports are covered with outwardly 25 opening, spring, closed flaps 25. The device forms the neck-valve system of the balloon, whereby, by lifting the sleeve valve 24 opens all wall ports to the atmosphere thus permitting the intake of cold air to lower the temperature in the balloon proper and effect the descent of the balloon system.

In its lowered position the lift-valve 24 closes all of the ports 23, thus forcing the balloon's contained air to circulate through 35 the furnace; whereby the air can be maintained at a given temperature with the minimum expenditure of fuel, and whereby, in this position of valve any undue internal pressure of air in the balloon due either to 40 temperature or expansion due to ascent to higher altitudes is relieved automatically through the outwardly opening vent valves 25.

The platform or balcony 11 supports the 45 furnace which consists of one or more annular or hollow stove chambers 30, Fig. 6, which contain a filling of refractory fragments, as of vitreous material, made incandescent by a flame from a suitable gas or retort burner 31. 50 It will be seen that because of the hollow center form of stove 30 the air will flow down on along and near the wet apron 32 and then will move in toward the stove and ascend along its exterior and interior cylindrical 55 faces and thence arise heated, in concentric columnar form to impinge against and be laterally diverted by the superjacent, inverted suspended, conical diaphragm 33 which thus disperses the hot air widely as it flows toward 60 the top of the balloon whence, by convection, it flows down along the inside wall of the envelop to be re-heated by the furnace.

The stove fuel tanks 34 are disposed between concentric walls of the car whence the 65 fuel is suitably conveyed to the burner.

The balcony 11 also supports water tanks 35 from which water is supplied to the curtain or apron 32 as by capillary attraction, to be absorbed by the heated air from the furnace.

Depending from the platform 11 is a fabric tube 38 through which air is injected into a balloon from a suitable blower 39 in the car for initial inflation after the bag has been drawn into mushroom position over the uprighted cage, as in Fig. 5. During flight or voyage the tube 38 remains in free open communication to the atmosphere and serves as a vent for any heavy gases of combustion which may form from furnace action.

Access may be had into the bag during air inflation for inspection and adjustment as needed, this being done through a normally closed manhole in the bottom of the bag section 2.

A different medium than air may be used for the lifting agent, such, for instance as the incombustible gas, helium.

It will be seen that when the cage is 70 uprighted as in Fig. 5, the diaphragm is supported by the cage crown and the inflating tube 38 is attached to the blower and this is operated; inflation will lift the bag to the dotted line form and the head valve 3 will close and the bag can be blown to about one-third its capacity, whereupon the furnace can be started. Sand bags are then attached and equator lines set to control complete inflation under joint action of the blower and the furnace.

When a landing is to be made the usual drag line is launched and on taking hold will turn the vessel to such a position as to cause the car skids 16 to come into presentation to the ground and effect a landing on the landing skids 18—14.

What is claimed is:

1. In a thermo-aerostat, a balloon section coated inside with a heat deflecting and radiating medium, and coated outside with a heat absorbing medium; whereby a maximum heat transmission is effected throughout the air within the balloon and a minimum of heat loss to outside atmosphere is permitted from the balloon.

2. In thermo-aerostat inflation, the method including the introduction of a vapor laden gas as a heat-absorbent conditioner of the air in the balloon and as a heat carrier between a source of heat and the air in the balloon.

3. In thermo-aerostat inflation, the method including the introduction of hot vapor laden gases as heat-absorbent conditioners of the air in the balloon and as heat carriers between a source of heat and the air in the balloon and as rarefiers of the mass density of the air in the balloon.

4. In thermo-aerostat inflation, the method including the introduction of a vapor laden fluid medium which has been highly heated

as a heat-absorbent conditioner of the air in the balloon and which acts as heat carrier between a source of heat and the air in the balloon, and as rarefier of the mass density of the air; whereby the air in the balloon is rendered more efficient as an aerostatic or lifting medium than atmospheric air alone can be.

5. In combination with a thermo-aerostat, a means maintained in a damp condition and exposed to air flow in the balloon space to form a liquid evaporator or vaporizer to condition the contained air and make it more absorbent of heat and means for heating the air passing adjacent to said means.

6. In combination with a thermo-aerostat, a furnace having a free central air flow passageway and including an annular burner and a superadjacent annular refractory radiator; whereby air circulating up past the furnace is made to assume a hot hollow column form dispersing its heat inwardly and outwardly at the same time to heat contacted air passing axially and externally along the furnace.

7. In combination with a thermo-aerostat, including a main body section in which is suspended an inverted, conical dispersing diaphragm whose upper rim is spaced from the body wall to provide ample convection current space, and an air heating furnace arranged in the neck of the section and whose top is well below the superspaced apposed point of the inverted conical diaphragm, whereby hot air from the heater impinges the said point and is then diverted upwardly to the rim of the diaphragm.

8. In a thermo-aerostat, a furnace, a balloon section having a neck-valve structure having manually operative means to admit cold air to the balloon, and including means operative to automatically effect a balance of pressure between the balloon content and the outside when the former is the higher.

9. In a thermo-aerostat, a car cage including a passenger basket, a platform above the basket, and having a balloon section ring frame; said basket, platform and frame being spaced apart and rigidly combined by a columnar bar system.

10. In a thermo-aerostat, a car cage including a passenger basket, a furnace platform above the basket, and landing and resting skids fixed on one side of the cage structure.

11. In a thermo-aerostat, means to treat the contained air, and including an annular humidifying apron about which air may flow downward along one face and upward about the other, and an annular heat radiator concentric with said apron; whereby a hollow cylindrical column heated, moistened air is delivered to the bag.

12. In a thermo-aerostat, means to treat the contained air, and including an annular humidifying apron about which air may flow

downward along one face and upward about the other, and an annular heat radiator concentric with said apron; whereby a hollow cylindrical column heated, moistened air is delivered to the bag; said radiator being disposed within the apron and spaced therefore to form an upflow passageway.

13. In a thermo-aerostat, a neck wall, a humidifying apron hung concentric within said wall, and a concentric annular furnace within said apron; whereby convection air in the bag is heated and humidified concurrently.

14. In a thermo-aerostat, a neck wall having valve means including a shiftable sleeve having ports registerable with ports in the wall and provided with breathing valves adapted to open to expel air from the aerostat and to close themselves to prevent ingress of cold air.

15. In a thermo-aerostat, a neck wall having valve means acting automatically to admit or dispel air according to atmospheric statics, and means for positively shifting the valve means to and from normal position.
